UNITED STATES PATENT OFFICE.

WILLIAM E. ATTERBURY, OF PORTLAND, OREGON.

SIGNALING DEVICE.

Application filed November 11, 1922. Serial No. 600,389.

To all whom it may concern:

Be it known that I, WILLIAM E. ATTERBURY, a citizen of the United States, residing at Portland, in the county of Multnomah and State of Oregon, have invented a new and useful Signaling Device, of which the following is a specification.

10 My invention relates to improvements in signaling devices for automobiles in which the intake manifold is connected with a right and left signal by means of a manually operated valve on the instrument board.

15 The objects of my invention are to provide a mechanism whereby right and left signals can be given by the simple shifting of a lever.

20 Another object is to provide an apparatus which is simple to construct and easy to manipulate.

25 Further objects and advantages are to be found in the construction and arrangement of parts as will be described hereinafter in the specification and particularly pointed out in the appended claim.

I attain these objects with the mechanism illustrated in the accompanying drawing in which:

30 Fig. 1 illustrates the general arrangement of my device, parts thereof being shown in section.

Fig. 2 is a vertical cross section through the valve illustrating the arrangement of the parts.

35 Similar numerals refer to similar parts throughout the several views.

Attached in any suitable manner to the instrument board of an automobile is a valve composed of a switch lever 1, a disk 2 rotated by the switch lever, and a housing 3 for the disk. Extending radially from the housing are the pipes 4, 5, 6, 7, and 8. The pipe 6 at the center is connected with the intake manifold, so that the suction from the latter will first be transmitted to a chamber 9 in the housing formed by the cut-away edge in the disk, and thence through such other pipes as may communicate with the chamber.

40 Traversing the automobile from one side to the other is a tube 10 which is divided in half by a center wall 11. Each half contains a piston 12, and a suitable signal 13 telescoped in the end of the tube 10 and attached to the end of the piston rod 14.

The wall 15 limits the outward movements 55 of the piston.

The pipes from the housing 3 are connected with the tube 10 in such a manner that, when the switch lever 1 stands in neutral position, the suction from the intake 60 manifold will be transmitted through the pipes 5 and 7 and draw the pistons toward the center wall, thus keeping the signals concealed in the tube 10.

If the switch lever be thrown toward the 65 right as indicated by the dotted line 16, suction in the pipe 5 will still be maintained and hold the left signal in concealment, but suction from the pipe 7 has been shut off, and communication with the pipe 4 has been 70 established instead, this draws the right piston outwardly into the dotted position 17 and the signal appears either in the shape of a painted or an illuminated arrow. Reversal of the switch lever withdraws the 75 right and projects the left signal.

The pins 18 limit the throw of the switch lever.

Having thus described my invention it will be seen that my objects have been accomplished, and, though I have shown the preferred form of construction, I reserve to myself the right to make minor changes providing I do not violate the spirit and principle of my invention. 85

I claim:

In a signaling device for automobiles, the combination of a horizontal tube extending from one side of the automobile to the other, a wall traversing the tube diametrically at 90 the center, a second wall traversing the tube diametrically on each side of the center wall, said second wall delimiting an air tight compartment on each side of the center wall, and a piston reciprocating within each compartment, with a flat circular housing below the tube, the axis of said housing lying within the plane of the center wall, a flat circular disk rotating air tight in said housing, said disk having a crescent shaped section in the top edge cut away thus leaving an air tight chamber between disk and housing, a suction inlet entering the rim of the housing radially and communicating with the chamber, a suction outlet at the medial center line of the housing at each side of the inlet and normally communicating with the chamber, each suction outlet proceeding 100 105

toward the tube and terminating in the compartment corresponding to the respective outlet and below the lowest piston inward stroke, a second suction outlet at the medial center line of the housing adjacent to the first named suction outlet and normally held closed by the rim of the disk, said second-

named outlet crossing the plane of the center wall and terminating in the compartment on the opposite side above the highest piston outward stroke.

Signed by me at Portland, Ore., this 6th day of November, 1922.

WM. E. ATTERBURY.
